(57) **CLAIM**

The ornamental design for a container body portion, as shown and described.

DESCRIPTION

FIG. 1 is a perspective view of a first embodiment of a container body portion showing our new design;

FIG. 2 is a front elevational view thereof, the rear elevational view being a mirror image thereof;

FIG. 3 is a top plan view thereof;

FIG. 4 is a bottom plan view thereof;

FIG. 5 is a perspective view of a second embodiment of a container body portion showing our new design;

FIG. 6 is a front elevational view thereof, the rear elevational view being a mirror image thereof;

FIG. 7 is a top plan view thereof; and,

FIG. 8 is a bottom plan view thereof.

It is understood that the bounds of the claimed design is represented by shade lines to the end of solid line of the container at the bottom and to the broken lines at the neck while all other broken lines are directed to illustrate environment. All broken lines form no part of the claimed design.
